RESISTANCE CONTROL VALVE FOR FUEL
INJECTION SYSTEM

Edward M. Greer, Great Neck, and Pellegrino Edward Napolitano, Brooklyn, N. Y., assignors to Greer Hydraulics, Inc., Brooklyn, N. Y., a corporation of New York

Application June 22, 1953, Serial No. 363,342

4 Claims. (Cl. 158—36)

This invention relates to the art of valves, more particularly of the resistance controlled type.

As conducive to an understanding of the invention, in one illustrative application thereof, it is noted that certain types of operating units such as engines, require for starting purposes an initial charge of a relatively large quantity of fuel and thereafter a continuous supply of a smaller quantity of fuel. Where the initial fuel charge is supplied by means of the injection of gas under pressure into the gas chamber of a fluid transfer unit such as a pressure accumulator whose fuel or liquid chamber is precharged with such fuel, in the event that fuel should flow from the liquid chamber into the gas chamber and through the system, into the source of gas under pressure, such fuel may explode with resultant destruction of the system and possible injury to personnel and damage to property.

It is accordingly among the objects of the invention to provide a system of the above type which will permit a spurt of gas under pressure to effect movement of the partition of a fluid transfer unit such as a pressure accumulator pre-charged with a fluid to deliver a relatively large quantity of such fluid to an operating unit, and upon leakage of such fluid past the partition, substantially immediately, without need for any manual operation, will cut off communication between the source of gas under pressure and such accumulator, which system has but few relatively simple parts which are not likely to become deranged even with long repeated use and which may readily be manufactured at low cost.

Another object is to provide a resistance controlled valve which upon application to the resistance unit thereof of a predetermined fluid, such as a liquid, or vapor of such liquid, will effect rapid and substantial increase of the resistance of such unit for actuation of the valve controlled thereby.

According to the invention from its broader aspect, the system comprises a reservoir from which a predetermined fluid such as liquid is supplied to an operating unit by means of a suitable pump. The system also includes a pressure accumulator of the type having a liquid chamber into which such liquid is also forced by the pump and a gas chamber with a movable partition between such chambers. The gas chamber of the accumulator is connected through a control chamber to a source of gas under pressure and a solenoid operated valve is interposed between such source and the control chamber, said valve being open during normal operation of the system. Positioned in the control chamber is a resistance unit which desirably comprises a rod of non-conducting material having a coating of conductive particles thereon, the ends of said rod being connected through suitable circuits to the solenoid operated valve, a source of current being included in such circuit to retain the valve open as long as the overall resistance of the conductive particles remains at a predetermined value. The resistance unit is so designed that in the presence of vapors of such predetermined liquid or if it is covered by such liquid, its resistance

2

will immediately increase a substantial amount to reduce the current flowing through the coil of the solenoid valve to a value below that sufficient to retain the valve open.

In the accompanying drawings in which is shown one or more of various possible embodiments of the several features of the invention, the single figure shows one illustrative embodiment of the invention.

Referring now to the illustrative embodiment of the invention shown in the drawings, the system desirably 10 comprises a reservoir 11 for a predetermined liquid which may be a fuel such as kerosene for example. The reservoir 11 is connected by line 12 to the inlet of a fuel pump 13 desirably driven by an electric motor 14 connected to a source of power, such as a battery 15, through a normally 15 open switch 16, and designed in the illustrative embodiment herein shown to deliver fuel under a pressure of 40 to 50 P. S. I. The outlet of pump 13 is connected through line 17 and check valve 18 to junction 19, the valve 18 permitting flow of fuel in direction only from such outlet.

The junction 19 is desirably connected by feed line 21, through solenoid operated valve 22, which has a coil 23 connected through switch 24 to a battery 25, to the operative unit, illustratively an engine 26 to be supplied with fuel. In addition, the junction 19 is connected by line 27 to the liquid supply port 28 of a fluid transfer unit such as a pressure accumulator 29 of conventional type such as that put out by Greer Hydraulics, Inc., of Brooklyn, New York.

The accumulator 29 is of the type which desirably 30 comprises a container 31 having a movable partition, preferably a bladder 32 therein which has a port connected to the gas supply port 33 of the accumulator for charging of such bladder. The port 33 is connected by line 34 to a junction 35 which in turn is connected by line 36 through valve 37 to the atmosphere. The junction 35 is also connected by line 38 to the port 39 of a control chamber 41 which desirably has a second port 42 at a level above that of port 39. The port 42 is connected by line 43 through solenoid operated valve 44, and line 45 to the outlet of a gas pump 46, driven by an electric motor 47. The motor is supplied with power as from a battery 48 through the normally open contacts 49, 51 of a time delay relay 52 connected through push button switch 53 to battery 54.

Positioned in control chamber 41 adjacent its floor 54 is a unit 55 which illustratively comprises a rod 56 of non-conducting material such as wood which desirably has a granular conductive coating 57 thereon, say of 55 sucrose carbon particles, and functions as a resistor. A metal cap 58 at each end of the rod 56 is contacted by the adjacent particles and has a lead 59 connected thereto and extending through the wall of the control chamber 41. One of the conducting caps 58 is connected to one side of a source of current, illustratively a battery 61, and the other cap is connected through the coil 62 of solenoid operated valve 44 and switch 63 to the other side of the battery 61.

In the operation of the system shown in the drawing, 60 the valve 37 is first opened to vent the related portion of the system to the atmosphere. The switch 63 is closed to complete a circuit from battery 61 through resistance unit 55 and the coil 62 of valve 44. The effective resistance of unit 55 is such that under normal conditions of operation when only air is present in control chamber 41, sufficient current will pass through unit 55 to energize coil 62, thereby opening valve 44. The motor 14 is then energized by the closing of switch 16 to actuate pump 13 to force fuel from reservoir 11 through check valve 18 and junction 19 into the accumulator 29 to charge the latter, the normally closed valve 22 preventing flow of fuel into the engine 26.

As fuel flows into the accumulator 29, the bladder 32 will be compressed and substantially all of the gas therein will be forced through line 34, junction 35, line 36 and open valve 37 to the atmosphere.

When the accumulator is fully charged with fuel, the valve 37 is closed and the switch 24 is actuated to energize coil 23 of valve 22 to open the latter so that fuel from reservoir 11 may flow to the engine.

As a greater quantity of fuel is needed when the engine is initially started, than is supplied by pump 13, at this time, a relatively large quantity of fuel may be forced into the engine by pressing push button switch 53. As a result a circuit will be completed from battery 54 to time delay relay 52 to close its contacts 49, 51 to complete a circuit from battery 48 to motor 47 to drive the gas pump 46, the length of time the pump operates being determined by the setting of time delay relay 52. Consequently gas under pressure will flow through line 45, open valve 44, line 43, port 42, control chamber 41, port 39, line 38, junction 35, line 34, through port 33 into the bladder 32 momentarily to inflate the latter. As a result, a spurt of a relatively large quantity of fuel will be forced from the accumulator port 28, through junction 19, line 21, open valve 22 into the engine 26. As the pump 13 is continuously operated, fuel will thereupon flow from the reservoir 11 into the engine 26 for continued operation thereof.

In the event that the engine should fail to start with the first charge of fuel injected therein, the switch 53 can again be closed momentarily to energize pump 46 to deliver a second charge of gas under pressure through the system as heretofore described.

In the event that the bladder 32 should break, either when it is momentarily inflated to deliver a spurt of fuel or during normal operation of the engine, such fuel would flow from the accumulator through lines 34 and 38 into control chamber 41. As the fuel starts to flow through the lines 34 and 38, the atmosphere in the line and hence in the chamber will be contaminated with such fuel and the vapor will flow around the resistance unit 55 seeping between the particles on rod 56. As a result of the use of such sucrose carbon particles, the vapor seeping therebetween would increase the overall resistance of the resistance unit almost immediately, thereby reducing the current flowing therethrough and through the coil 62 of valve 44 to a point insufficient to retain the valve open. Thus the valve would close and such closing will occur before any fuel can pass through the valve 44 into the gas pump 46, which might cause explosion with consequent harmful results.

Although in the system above described, sucrose carbon particles have been used in conjunction with kerosene, it is of course to be understood that it is within the scope of the claims to utilize other types of conducting particles having a given overall resistance in the presence of one fluid and a different overall resistance in the presence of a second fluid.

It is also within the scope of the invention to utilize accumulators of types other than those with a bladder, i. e., a piston-type accumulator for example, and to use the system in conjunction with operating units other than engines, i. e., such as hydraulic motors.

As many changes could be made in the above construction, and many apparently widely different embodiments of this invention could be made without departing from the scope of the claims, it is intended that all matter contained in the above description or shown in the accom-

panying drawings shall be interpreted as illustrative and not in a limiting sense.

Having thus described our invention, what we claim as new and desire to secure by Letters Patent of the United States is:

1. A system of the character described comprising a reservoir for liquid, a pump, a line connecting the reservoir to said pump, a fluid transfer unit having a liquid supply port, a gas supply port and a movable partition intervening between said ports, means connecting the output of said pump to said liquid supply port to charge said fluid transfer unit with liquid, a liquid outlet line in communication with said liquid supply port, a control chamber having two ports, means providing communication between one of said ports and said gas supply port, a vent line connected to said last-named communicating means, a valve in said vent line, means to connect a source of gas under pressure to the other port of said control chamber, a valve between the gas source and said other port, said last named valve being of the solenoid operated type, a resistance unit in said control chamber electrically connected to said solenoid operated valve to control the flow of current therethrough, said resistance unit normally permitting sufficient current to flow through said solenoid valve to retain the latter in open condition, said resistance unit being designed to increase its resistance in the presence of an atmosphere containing vapors of such liquid, whereby if said partition should break and permit flow of liquid from said fluid transfer unit into said control chamber, the resultant liquid vapors in said control chamber will cause actuation of said solenoid valve to cut off communication between said gas source and the associated port of the chamber, to prevent flow therebetween.

2. The combination set forth in claim 1 in which said movable partition is a deformable bladder connected to said gas supply port.

3. The combination set forth in claim 1 in which a source of gas is provided, comprising a pump, an electric motor is operatively connected to said pump to drive the latter, a time delay relay having a pair of normally open contacts, means connecting said contacts to said motor to energize the latter upon closing of said contacts, and means to energize said relay.

4. The combination recited in claim 1 in which said resistance unit comprises a rod of non-conducting material having a coating of conductive particles thereon forming a continuous resistor, said conductive particles having a given overall resistance in one fluid and a greater overall resistance in the second fluid.
